CLAIM

The ornamental design for a receiver holder, as shown and described.

DESCRIPTION

An article to which my new design is applied is a holder for holding a receiver. The receiver is for receiving in vivo information transmitted from a medical swallowable endoscope (the so-called capsule endoscope), where the receiver and the capsule endoscope constitutes a wireless in vivo information acquiring system. The holder is attached to a belt put on the user's waist with a buckle and its shoulder strap is put on the user's shoulder while holding the receiver.

FIG. 1 is a right-front perspective view of a receiver holder showing my new design;

FIG. 2 is a left-rear perspective view thereof;

FIG. 3 is a front view thereof;

FIG. 4 is a rear view thereof;

FIG. 5 is a plan view thereof;

FIG. 6 is a bottom view thereof;

FIG. 7 is a right side view thereof;

FIG. 8 is a left side view thereof;

FIG. 9 is a front view thereof, with the straps shown in an open position;

FIG. 10 is a rear view thereof, with the straps shown in an open position;

FIG. 11 is a left-front perspective view illustrating the usage thereof; and,

FIG. 12 is a right side view illustrating the usage thereof.
